UNITED STATES PATENT OFFICE.

REINHARD MANNESMANN, OF REMSCHEID, GERMANY.

MANUFACTURE OF SEAMLESS TUBES.

SPECIFICATION forming part of Letters Patent No. 361,957, dated April 26, 1887.

Application filed March 28, 1887. Serial No. 232,792. (Model.) Patented in England January 27, 1885, No. 1,167; in France January 27, 1885, No. 168,433; in Belgium January 27, 1885, No. 67,667; in Germany January 27, 1885, No. 34,617; in Italy January 26, 1886, No. 7,925; in Luxembourg June 20, 1886, No. 704; in Spain August 21, 1886, No. 9,537, and in Austria-Hungary September 18, 1886.

To all whom it may concern:

Be it known that I, REINHARD MANNESMANN, of Remscheid, Germany, have invented a certain Improvement in Apparatus for Manufacturing Seamless Tubes from Solid Metallic Blanks, of which the following is a specification.

This invention relates to the manufacture of seamless tubing from solid metallic blanks by means of apparatus of the type which I have described in other pending applications for patents, the characteristic features of the mode of producing tubing in such apparatus being that a solid metallic blank suitably heated is passed endwise between diagonally-acting rolls the working-faces of which converge. I have in another application described the combination for same purposes of such rolls with a comparatively slender rod adapted to be loosely contained within the tube in process of formation, the end of which rod abuts against and serves to hold back the solid central portion of the blank. I have also described in another application the employment of rolls of the character referred to in combination with a conical mandrel placed midway between the working-faces of the rolls and used for smoothing the inner surface and also for determining the inner diameter of the tube. In those cases, however, the holding-back bar or forming-mandrel has always been a passive factor in the combinations described. The said factor has been prevented from endwise movement, and in some cases from rotatory movement, though it has usually been left free to be rotated by the frictional bearing upon it of the rotating blank, within the tubular part of which it has been contained.

The present invention consists in the combination of diagonally-acting rolls having convergent working-faces with a centrally-placed mandrel, which is preferably conical, and the surface of which is provided with spiral corrugations, preferably of increasing pitch, the mandrel either being held stationary or revolved in the same direction as the blank, but at a slower speed, or revolved in the opposite direction from that of the blank for the purpose of causing the spiral corrugations in the

conical mandrel to engage the metal near the place within the blank where the tubular formation is initiated, and to draw such metal forward, and thus co-operate with the external diagonally-acting rolls in forming a tube of prescribed interior and exterior diameter. 55

Machines for diagonally rolling metallic bars or blanks passed endwise between their working-faces have heretofore been used for various purposes, and, being well known, do not need description in detail herein. The accompanying drawings therefore embrace only those features of construction which are peculiar to diagonal rolling apparatus embodying the present invention.

The drawings are as follows: Figure 1 is a top view, and Fig. 2 is a side elevation, of a portion of a diagonal rolling-machine employing a mandrel the conical head of which is spirally grooved and is placed midway between the convergent working-faces of two oppositely-inclined conical rolls, the vertical planes of the axes of which are parallel. Figs. 3, 4, 5, 6, and 7 are each top views, showing in horizontal section a metallic blank at various stages of its progress between the working-faces of the rolls, during which it is transformed into a hollow body or tube open from end to end.

For convenience of description, it is assumed that in the structure illustrated in the drawings two diagonally-acting conical rolls are arranged upon either side of a horizontal mandrel, and that the vertical planes of the oppositely-inclined axes of the rolls are parallel.

It will of course be understood that the diagonally-acting rolls may be arranged one above and the other below the mandrel, and also that the vertical planes of the axes of the rolls need not necessarily be parallel.

The working-faces of the conical rolls A a 90 are generally provided with spiral corrugations, as shown in Fig. 3.

The blank B is properly centralized for delivery to the rolls by being placed within the guide-tube B', which is rigidly clamped to the table B' immediately adjoining the rolls. From the guide-tube B' the blank B is fed into the wider end of the space between the working-

faces of the rolls, and by the pinching effect to which it is immediately subjected has the concave recess *b* formed in its forward end. Soon after the formation of the concave recess 5 *b* the forward end of the blank is brought into collision with the conical mandrel *C*, which for a portion of its length is provided with a spiral groove or grooves, *C'*, the pitch of which preferably becomes gradually coarser from the 10 point toward the base of the cone.

The base of the mandrel is provided with the projecting tongue *C'*, which is in the form of the frustum of a pyramid, and is loosely contained in the flaring rectangular socket *d*, 15 formed in the end of the mandrel-shaft *D*.

At its opposite end the mandrel-shaft *D* is squared and loosely contained in the quadrangular socket *e*, formed in the end of the shaft of the pinion *E*, and suitable gearing is provided for rotating the pinion *E* in such direction and at such speed as may be desired. 20

Inasmuch as the blank in process of transformation into a tube is rotated by the action upon it of the rolls, the mandrel, if held stationary, will perform its function of assisting in drawing forward the metal engaged in its spiral grooves; but in some cases it may be desirable to lessen the extent to which the mandrel acts in this particular, which can be 25 done by imparting rotation to the mandrel in the same direction as that of the blank, but at less speed. On the other hand, it may be desirable in some cases to increase the effectiveness with which the spiral grooves perform 30 their function, and to effect this result the mandrel can be rotated in the direction opposite to that of the direction of rotation of the blank.

Progressive stages in the transformation of 40 the solid blank into a tube are illustrated in Figs. 3, 4, 5, 6, and 7.

The mandrel may, if desired, be made ellipsoidal in cross-section, but is preferably made circular in cross-section, as represented in the 45 drawings. It may be spirally grooved for its entire length or upon any portion of its surface, and its spiral grooving may have any desired pitch or variation in pitch.

The employment of a spirally-grooved mandrel as an active factor, in combination with the diagonally-acting rolls, for effecting the 50

transformation of a solid metallic blank into a tube is especially desirable in operating upon blanks composed of soft and ductile metals, and in operating upon such metals it 55 will not in all cases be necessary to have any portion of the working-faces of the diagonally-acting rolls corrugated, although such corrugations may of course be provided, if desired.

It will be obvious that the spirally-grooved 60 conical mandrel, held stationary or rotated at a different speed or in a different direction from that imparted to the blank by the diagonally-acting rolls, may be employed for the purpose of enlarging the internal diameter of 65 a hollow blank, and of co-operating with the diagonally-acting rolls in drawing out a hollow blank into a tube having a shell of prescribed thickness.

I claim as my invention—

1. In diagonal tube-rolling apparatus, the combination, as herein set forth, of diagonally-acting rolls the working-faces of which are suitably convergent with a grooved or corrugated mandrel interposed between opposite 75 portions of the working-faces of said rolls, and means for holding the said mandrel stationary, or for rotating it at a different speed or in the opposite direction from the speed and direction of rotation acquired by a solid or 80 hollow blank during its passage between the working-faces of the rolls.

2. The improvement in the art of transforming a solid metallic blank into a tube, which consists in progressively rolling and 85 drawing the metal composing the exterior portion of the blank inwardly and forwardly over the pointed end of a grooved or corrugated mandrel by means of diagonally-acting rolls having suitably-convergent faces, and 90 simultaneously drawing forward the metal from the interior portion of the blank by holding the said grooved or corrugated mandrel stationary, or by rotating it at a different speed or in the opposite direction from the 95 speed and direction of rotation acquired by the blank in its passage between the converging working-faces of the rolls.

REINHARD MANNESMANN.
